[57] CLAIM

The ornamental design for a combined shelves and towel rack, as shown and described.

DESCRIPTION

FIG. 1 is a front elevational view of the combined shelves and towel rack showing my new design;

FIG. 2 is a top plan view thereof;

FIG. 3 is a rear elevational view thereof;

FIG. 4 is a bottom plan view thereof;

FIG. 5 is a side elevational view, the side opposite being a mirror image thereof;

FIG. 6 is an enlarged sectional view taken on line 6—6 of FIG. 1;

FIG. 7 is a fragmentary sectional view taken on line 7—7 of FIG. 1.
